ELECTRICAL CUT-OUT

Ralph W. E. Moore, Pittsburgh, Pa., assignor to
National Electric Products Corporation, Pittsburgh, Pa., a corporation of Delaware

Application January 11, 1934, Serial No. 706,202

5 Claims. (Cl. 200—119)

This invention relates to electrical cutout organizations and particularly to cutout organizations of the type which protect circuits with plug fuses.

5 The electrical supply for buildings (for example) is customarily distributed from a distributing cabinet in which are located fuses for protecting the various electrical circuits individually. Frequently this cabinet is also provided with manually operable switches for cutting circuits in and out. To minimize tampering, the distributing cabinets in residences and many other installations are so arranged as to give the consumer no more access to the wiring and electrical circuits than is necessary. This means that the elements are all permanently enclosed except that the fuse plug elements themselves are accessible for replacement and that the handles of switches are accessible for operation of the 10 switches. Even this degree of accessibility permits more or less easily accomplished tampering which may endanger the circuits with resultant fire and personal hazard. For example, the consumer may replace a burned out fuse with a fuse 15 having a rating higher than the safe carrying capacity of the circuit. Or, when a fuse burns out the consumer may bridge the fuse socket with a coin, wire, or tin foil thus leaving the circuit completely unprotected.

20 An object of the present invention is to provide a permanent cutout and/or controlling organization which will make it very difficult indeed for a consumer to so tamper with the distributing cabinet as to leave a circuit unprotected.

25 Another object of the invention is to provide a permanent cutout and/or controlling organization which will prevent the insertion of fuses having ratings higher than the safe carrying capacity of the respective circuits.

Fig. 1 is a view with parts broken away showing a typical distributing cabinet installation embodying the present invention. Considering the 30 box as mounted on a wall the view is an elevation.

Fig. 2 is an approximately full sized figure showing a fuse receptacle of the present invention, the figure being a plan view if the receptacle be considered as being in a horizontal position.

Fig. 3 is an enlarged vertical section taken approximately on the line 3—3 of Fig. 2.

Fig. 4 is a fragmentary view showing the end 35 of a fuse plug in the position it occupies when

being advanced for insertion into the socket shown in Fig. 3.

Reference will first be had to Fig. 1. Screwed, or otherwise secured to the bottom (or back) of a metal distributing cabinet 10 are a plurality of fuse receptacle blocks such as 11, 12 and 13. Blocks such as 11 are adapted to receive two fuses which may be used (for example) to fuse one side of two separate circuits, the other side of each circuit being unfused and connected to 10 a grounded neutral bar 9. Blocks such as 12 are adapted to receive four fuses for fusing (for example) both sides of two individual circuits. Blocks such as 13 are adapted to receive four fuses for fusing four wires as desired, 15 and in series with each of the fuses is a manually operable single pole snap switch controlled by a handle 14. The connection to the center contact of each of the fuse sockets is made by bus bars 15 (four shown) which pass beneath the fuse blocks; and connection to the shell contact of each of the fuse sockets is made by suitable wiring 17. Covering the wiring and fuse blocks is a rigidly secured cover plate which is merely provided with suitable apertures through which the fuses can be inserted into the fuse sockets and through which the handles 14 of the switches project for actuation. At its top 20 the cover plate 18 may have a separately removable section 18^a to give an electrician access to the terminals of bus bars 15 and to the grounded neutral bar. Hinged to the trim 19 is a metal door 19^a which closes over the fuses and switch handles.

Reference will now be had to Figs. 2 and 3 which show the structural details of the fuse receptacles, a receptacle such as 11 being specifically shown to avoid needless duplication of similar parts. An insulating base 20, of suitable molded material such as a phenol condensation product or porcelain, is provided with leg portions 21 and 22 which are adapted to contact with the bottom of the distributing cabinet; and between these leg portions extends one of bus bars 15, threaded into which is a screw 24. A flat metal terminal member 25 lies in the bottom of cuplike depression 26 and extends through aperture 27, beyond which it is provided with a screw 28 for making wiring connection to the cutout base. The terminal member 25 is secured in place in the insulating base 20 by screws 29—29. Secured to terminal member 25 by several screws 30 (one shown) is a sheet metal threaded screw socket 31 which preferably is of smaller diameter than a standard shell so it will reject the plug 35

fuses which have heretofore been in common use. Screwed into the socket 31 is a fuse selector 32 made of suitable molded insulating material such as a phenol condensation product. This fuse selector 32 is provided with a spring barb 33, the point of which engages the surface of shell 31 and prevents removal of the fuse selector 32. This barb is of the same general type as barb 35 shown in Fig. 2 of my copending application Serial No. 699,652, filed November 25, 1933. Within the fuse selector 32 is a movable circuit making and breaking plug 34 provided at one end with a head 35, and at the other end with a washer 36, held in place by riveting as at 37. Member 34 is normally biased into the position shown in the drawing by helical spring 38; and when the member 34 is reciprocated, washer 36 moves back and forth in a recess 39. Holes 40 are provided to receive screws for securing the cutout base 20 in the service box; and vertically extending insulating partitions 41 separate wiring connections 28 one from another.

The receptacle is adapted to receive a fuse of the type fully disclosed in my copending application Serial No. 699,652, filed November 25, 1933, but Fig. 4 of the present drawing shows the portion of the fuse which is received by and cooperates with the present fuse receptacle. The fuse body of suitable molded insulating material has 30 a depending central portion 45 from which projects a metal contact member 46. Surrounding and spaced from the central member 45 is an annular skirt 47 outside of which is a screw-threaded sheet metal thimble 48 adapted to screw into the shell 31. A fuse link, located in the upper portion of the fuse, connects central contact 46 with shell 48; and when the fuse blows, gases escape through ports, one of which is shown at 49.

40 The fuse is installed in the base merely by screwing it in place in the shell 31 in an obvious manner. Center fuse contact 46 engages circuit making and breaking member 34, advancing it against the action of spring 38 until it engages screw 24 that is in electrical connection with the bus bar 15. Center portion 45 of the fuse is of such size that it can enter the space vacated by head 35 as the latter is advanced; and skirt 47 is of such dimensions that it telescopes into the 50 annular space about outer wall 43 of the fuse selector 32. The outer vertical wall of the fuse selector 32 is provided with grooves 44 which permit the escape of gases issuing from port 49 in the fuse.

55 In fuses of different rating the skirt 47 has different thicknesses, with the thicker skirts 47 being assigned to the fuses of higher rating. Fuse selector 22 is so sized as to receive a fuse of the rating which the circuit is designed to carry. Fuses of lower rating are of course harmless and may be inserted in the circuit since the skirt 47 will be of less thickness than the width of the space around wall 43. But fuses having a rating 60 higher than the safe carrying capacity of the circuit have a skirt 47 which is thicker than the annular space about wall 43, and hence such fuses of higher rating are rejected by the fuse selector 32 and cannot be inserted in the receptacle.

70 It will be apparent that the circuit cannot be bridged by the insertion of coins and the like because when a fuse is removed the circuit is automatically broken by the outward movement of circuit making and breaking member 34. Shell 75 31 may extend to such a small height above the

top of fuse selector 32 as to prevent a blown fuse from being used to hold circuit making element 34 down with a plug or the like inserted under the fuse. The telescoping of skirt 47 over the fuse selector and the telescoping of central member 45 into the space vacated by head 35 serve to rupture any tin foil which may be inserted into the socket.

It will be seen that the present invention provides a permanent cutout installation which virtually prevents unauthorized and ill advised persons from over fusing the circuits or bridging blown out fuses. The invention may of course be embodied in various specific forms and hence the foregoing disclosure is merely illustrative in 15 compliance with the patent statutes, and the invention is not to be limited except by the scope of the appended claims.

I claim:

1. A fuse receptacle comprising: a base of insulating material, the base being formed with a socket having a bottom and a recess extending below the center portion of the bottom; a cup-like fuse-receiving contact positioned in said socket; the bottom of the cup formation being adjacent to the bottom of said socket and having an aperture overlying said recess; a center current-carrying contact positioned in said recess below the bottom of said socket; a fuse selector of insulating material positioned in the lower portion of said fuse-receiving contact; and a circuit breaker carried by said fuse selector and cooperable with said center contact, the circuit breaker being normally biased into open position but being automatically movable into engagement with said center contact by the insertion of a fuse.

2. A fuse receptacle comprising: a base of insulating material, the base being formed with a socket having a bottom and a recess extending below the center portion of the bottom; an annular fuse-receiving contact lining said socket; a center current-carrying contact positioned in said recess below the bottom of said socket; a fuse selector of insulating material positioned in the lower portion of said fuse-receiving contact, said selector receiving fuses up to a given rating and rejecting fuses of higher rating; and a circuit breaker carried by said fuse selector and cooperable with said center contact, the circuit breaker being normally biased into open position but being automatically movable into engagement with said center contact by the insertion of a fuse.

3. A fuse receptacle comprising: a base of insulating material, the base being formed with a socket having a bottom and a recess extending below the center portion of the bottom; a cup-like fuse-receiving contact positioned in said socket, the bottom of the cup formation being adjacent to the bottom of said socket and having an aperture overlying said recess; a center current-carrying contact positioned in said recess below the bottom of said socket; a fuse selector of insulating material positioned in the lower portion of said fuse-receiving contact, said fuse selector having an annular extension of insulating material projecting through the aperture in the bottom of said fuse-receiving contact; and a circuit breaker carried by said fuse selector and cooperable with said center contact, the circuit breaker being normally biased into open position but being automatically movable into engagement with said center contact by the insertion of a fuse.

4. A fuse receptacle comprising: a base of

insulating material, the base being formed with a socket having a bottom and a recess extending below the center portion of the bottom; a threaded cup-like fuse-receiving contact positioned in said socket, the bottom of the cup formation being adjacent to the bottom of said socket and having an aperture overlying said recess; a center current carrying contact positioned in said recess below the bottom of said socket; a fuse selector of insulating material screwed into and permanently secured in the lower portion of said fuse-receiving contact; and a circuit breaker carried by said fuse selector and cooperable with said center contact, the circuit breaker being normally biased into open position but being automatically movable into engagement with said center contact by the insertion of a fuse.

5. A fuse receptacle comprising: a base of

insulating material, the base being formed with a socket having a bottom and a recess extending below the center portion of the bottom; an annular fuse-receiving contact lining said socket; a center current-carrying contact positioned in said recess below the bottom of said socket; a fuse selector of insulating material positioned in the lower portion of said fuse-receiving contact, the fuse selector having a single centrally located cylindrical extension projecting upwardly within the fuse-receiving contact and acting to receive fuses of various ratings up to a certain rating and reject fuses of higher rating; and a circuit breaker carried by said fuse selector and cooperable with said center contact, said circuit breaker comprising a reciprocatory vertical member biased upwardly by a spring and adapted to be depressed by the insertion of a fuse.
